Filed Nov. 20, 1961, Ser. No. 67,589

Term of patent 14 years

(Cl. D30—1)

FIG. 1 is an elevational view of one side of a resilient gun recoil pad embodying our new design, the opposite side of the pad being the mirror image of that illustrated;

FIG. 2 is a front elevation of the pad;

FIG. 3 is a rear elevation of the pad;

FIG. 4 is a top plan view of the pad;

FIG. 5 is a bottom plan view of the pad; and

FIG. 6 is a fragmentary perspective view illustrating the depth of the recesses in the sides of the pad.

We claim:

The ornamental design for a resilient gun recoil pad, as shown and described.
